UNITED STATES PATENT OFFICE.

MELVILLE A. CLARK, OF SYRACUSE, NEW YORK.

HARP-HARNESS.

1,133,615.

Specification of Letters Patent. Patented Mar. 30, 1915.

Application filed January 5, 1912. Serial No. 669,572.

To all whom it may concern:

Be it known that I, MELVILLE A. CLARK, of Syracuse, in the county of Onondaga, in the State of New York, have invented 5 new and useful Improvements in Harp-Harness, of which the following, taken in connection with the accompanying drawings, is a full, clear, and exact description.

This invention relates to certain improvements in body supports for harps for supporting relatively small sized harps upon the body of the player.

The main object is to provide simple means for attaching the harp to the body 10 in such manner as to support the harp firmly in playing position independently of any external supporting means so as to readily respond to various rapid movements of the body as in walking, dancing or other 15 movements without liability of displacement and at the same time permitting freedom of movement of all parts of the body, leaving the hands free for manipulation and turning of the strings with even greater 20 facility than when supported in the usual manner.

One of the specific objects is to provide the harp with a body brace capable of holding the harp the desired distance from the 25 body and at the same time bracing it against undue lateral swaying movement and in connection with the body loop serves to hold the harp in playing position at substantially right angles to the front of the body.

Another object is to enable the harness to be easily and quickly detached from the harp and body so that the harp may be used in the usual manner when desired.

40 A still further object is to provide the base of the harp with a non-slipping leg rest attachment for engaging the leg and supporting the harp thereon when the player is in a sitting posture.

45 Other objects and uses will be brought out in the following description.

In the drawings—Figure 1 is a perspective view of a harp and harness attachment in operative position upon the body of a player. Fig. 2 is an enlarged longitudinal vertical sectional view through the rear

side of the harp column and adjacent portions of the harness in operative position thereon, the lower end of the base supporting strap being shown in section. Fig. 3 55 is a still further enlarged vertical sectional view of the upper end of the body brace shown in Fig. 2. Fig. 4 is a top plan of the portion of the body brace shown in Fig. 3. Fig. 5 is a perspective view of the 60 detached body brace. Fig. 6 is a perspective view of the upper attaching end of the body loop. Fig. 7 is an inverted plan of the lower end of the body loop and adjacent portion of the harp base showing 65 the means for adjustment of the loop to bodies of different size. Fig. 8 is an enlarged perspective view of the detached leg engaging pad for the base of the harp. Fig. 9 is a longitudinal sectional view of 70 the same pad and adjacent portion of the harp base. Fig. 10 is a transverse sectional view of a leg pad and harp base showing the hinge connection for permitting relative tilting movement of the base and leg pad. 75 Fig. 11 is a transverse sectional view of a modified form of attaching means for the leg pad to the harp base.

This harp support comprises a body loop 80 —1—, a body brace —2— and a leg pad 80 —3—, the body loop preferably consisting of a flexible strap of leather or other suitable material of sufficient length to pass from the upper front of the shoulder around the back and waist and return to 85 the front of the body for attachment to the upper and lower portions of the harp as —A— in a manner presently described.

The harp is provided with the usual hollow column having its rear side formed 90 with a series of openings —a— for the exit of the sound waves from the sounding board, thus forming lower, intermediate and upper cross bars or shoulders —a'—.

The upper front end of the body loop 95 —1— terminates in a hook-shaped fastening device —4— preferably of metal and of such dimensions as to readily pass through the opening —a— and engage with the upper shoulder —a'— as shown more 100 clearly in Fig. 2.

The lower end of the body loop —1— is

provided with an adjustable section —5— connected thereto by a buckle —6— to permit the body loop to be readily adjusted to different sizes of harps or to different 5 individual players, the section —5— terminating in a metal clasp —6— having a key slot —7— for the reception of a headed pin or stud —8— on the underside of the base of the harp near its rear edge, thus permitting 10 the lower end of the body loop to be easily and quickly attached to or detached from the harp.

The body brace —2— comprises a laterally elongated bar or plate —9— which is 15 curved longitudinally to conform as nearly as possible to the front portion of the body of the player against which it is adapted to rest and is provided with forwardly diverging arms —10— and —11— having hook-shaped extremities —12— and —13— for interlocking engagement with the lower and intermediate bars —a'— of the harp.

The hooks —4—, —12— and —13— constitute attaching members for supporting 25 the harp upon the body in proper position for playing and for this purpose the attaching members —12— and —13— are disposed in an upwardly and rearwardly inclined plane at an angle to the vertical plane 30 of the plate —9— so as to support the harp at the desired angle for convenient manipulation of the strings and may be readily passed through the adjacent opening —a— for attachment to or removal from the 35 bars —a'—.

As a further precaution for preventing accidental detachment of the body brace or harp from each other, I have provided the upper arm —11— with a movable catch 40 —14— which, in this instance, is journaled on the hook —13— and is adapted to be moved to and from a position across the upper side of the adjacent bar —a'— by means of a finger piece —15— as best seen 45 in Figs. 2, 3 and 4.

It is now clear from the foregoing description that when the body loop —1— and brace —2— are properly adjusted on the body, the body loop serves to support 50 the weight of the harp, while the body brace serves to hold it in proper relation to the body, leaving the arms free to manipulate the strings in the usual manner, and at the same time permitting the player to move 55 about with more or less rapidity while playing without liability of displacing the harp from its playing position. The same is also true when the player is in a sitting position except that under such conditions, I prefer 60 to rest the weight of the harp upon the legs and in order to prevent lateral slipping of the harp upon the legs I have provided the pad —3— which is preferably hinged for swinging movement to the underside of the 65 base of the harp column.

In order that the pad may readily adjust itself to the contour of the leg of the player, I have made it in sections —16— and —17— hinged together end to end at —18— so that one part may tilt relatively to the other, each section being provided with a serrated lower facing —19— of rubber or equivalent material which will frictionally engage the leg of the player and hold the harp against lateral slipping thereon. 75

The section —16— is preferably provided with a fixed hinge section or bearing —20— journaled upon a hinge pin —21— which is secured at one end by a screw —22— to the underside of the base of the harp, the opposite end of the hinge pin being free to permit the bearing —20— to slide thereon for removal or replacement of the pad.

In Fig. 11 I have shown a similar pad —3— omitting the bearing —20— and having its section —16— slidably interlocked with a stationary loop —23— on the underside of the base of the harp, said loop being preferably secured to said base in an inclined position through the medium of an 90 interposed wedge-shaped member —24— which is also rigidly secured to the harp base. 85

In both instances the pad may be adjusted laterally either along the hinge pin —21— 95 shown in Fig. 8 or along the guide loop —23— shown in Fig. 11 to conform to the position of the leg relatively to the harp.

In placing the harp in position upon the body, it is simply necessary to throw the 100 strap or body loop —1— around the right-hand shoulder and to then lift the harp into proper position and attach the upper hook —4— and lower clasp —6— to their respective shoulders —a'— and stud —8— after 105 which the body brace —2— may be placed in operative engagement with the corresponding shoulders —a'— with the plate —9— resting against the front of the body, the body brace being held in position 110 against downward displacement by the proper adjustment of the locking member —14—, whereupon the harp is ready for playing either in a sitting or standing posture. In reverse manner the body loop and 115 brace may be detached from the harp and the latter used in the usual manner, under which conditions the leg pad —3— may be removed entirely or shifted under the base and the section —19— folded upwardly 120 against the section —16— out of the way.

What I claim is:

1. In combination with a harp-column having openings therein, a brace having a laterally extending curved plate for engagement with the body of the player and arms rigidly secured to the plate and provided with attaching members entering the openings and engaged with the harp-column. 125

2. In combination with a harp-column 130

having transverse bars spaced apart one above the other, a brace having a laterally extending curved plate for engaging the body of a player, and forwardly diverging 5 arms rigidly secured to the plate and having their forward ends hook-shaped and engaged with the undersides of said bars.

3. In combination with a harp-column, a brace having a laterally elongated plate and 10 forwardly diverging arms rigidly secured thereto and having their front ends attached

to the harp-column, the lower arm projecting forwardly beyond the vertical plane of the upper arm when in use.

In witness whereof I have hereunto set 15 my hand on this 27th day of December, 1911.

MELVILLE A. CLARK.
